PRESSURE REGULATOR FOR DISPENSING APPARATUS

William B. Kochner, deceased, late of St. Louis, Mo., by
Regina L. Kochner, administratrix, St. Louis, Mo.,
assignor to Knapp Monarch Company, a corporation
of Delaware

Filed Oct. 14, 1963, Ser. No. 316,492
9 Claims. (Cl. 137—505.25)

The present invention relates generally to a dispensing device, and more particularly to an improved valved dispenser head for pressurizing and regulating eduction flow from a liquid container of the type disclosed in R. S. Knapp et al. Patent No. 2,842,293, having a common assignee herewith.

This application is a continuation-in-part of copending application Serial No. 842,730 filed September 28, 1959 for Dispensing Apparatus, now abandoned.

The sale of beer and similar ebullient liquids in relatively large containers, particularly gallon size, for home use necessitates the provision of a simple, efficient and reliable dispensing means for providing a constant pressure on the beer within the container and for regulating eduction flow therefrom. It is desirable to provide dispensing means of this type wherein carbon dioxide pressurization by means of a pierceable bulb with gas therein at very high pressures may be employed. Several difficult problems arise, however, in attempting to adapt very high gas pressure bulb pressurization to the dispensing of readily foamable, ebullient liquids. Although pressure regulating means have been known for maintaining a relatively constant, predetermined supply pressure from such very high pressure bulbs, such as in Lamb Patent No. 2,649,661, the sudden high pressure surges which characterize the application of initial gas supply as the very high pressure bulb is pierced, or which may occur inadvertently from slight inaccuracy of operation of a pressure regulator, have resulted in a highly undesirable pressure "over-run" and have caused excessive foaming when such ebullient liquids as beer are dispensed. In order to maintain a constant pressure on the liquid in an efficient manner throughout the dispensing life of the container, it is necessary to prevent liquid from working its way up into the pressure regulating structure of the pressurizing means. It is also of importance to control the amount of foaming of beer and the like as a result of agitation and mixing during flow through the discharge valve means. Still further, it is important to eliminate pockets in the pressurizing and dispensing structures in which beer might be captured and become sour during storage.

It is a primary object of this invention, therefore, to provide a dispensing device of the type described having novel pressure regulator means for controlling initial pressure over-run, for providing a constant dispensing pressure, and for preventing liquid back-up.

It is another object to provide a dispensing device of the type described having a self-closing, manually-actuated push button type of valve for regulating dispensing flow through a spigot without excessive foaming.

It is a further object to provide a dispensing device of the type described having a novel eduction tube for effecting a spiral flow pattern to reduce discharge pressure and facilitate the control of foaming.

It is still another object to provide a dispensing device of the type described having a novel arrangement and orientation of parts to effectively preclude liquid collection in stagnant pockets and thereby avoid the risk of souring during storage.

With these and other objects in view, the invention consists in the construction, arrangement and combination of the various parts of the dispensing apparatus whereby

2

the objects contemplated are obtained as hereinafter more fully set forth, pointed out in the claims and illustrated in the accompanying drawing, wherein:

FIGURE 1 is a top plan view showing a container having a pressurizing and dispensing device constructed in accordance with the present invention operatively mounted therewith;

FIG. 2 is a side elevational view of the assembly shown in FIGURE 1, with parts broken away and in section to show details of internal construction;

FIGURE 3 is a fragmentary vertical cross-sectional view taken substantially as indicated by the line 3—3 on FIGURE 2; and

FIGURES 4, 5 and 6 are vertical cross-sectional views taken substantially as indicated by the lines 4—4, 5—5, and 6—6 on FIGURE 1.

Referring now to the drawing, there is shown a container 10 of the type used for storing liquids and capable of being internally pressurized. The container 10 is formed with a generally cylindrical side wall 12, and a bottom wall serving to support the container in a generally upright position when disposed on a supporting surface. The bottom wall is centrally upwardly dished at 14 in a spherically curved manner, and is annularly upwardly conical at 16, outwardly of the central convexity 14, to increase the strength of the container, to improve upright support stability, and to facilitate substantially complete fluid withdrawal.

The container 10 provides a top wall centrally downwardly dished at 18, and annularly downwardly conical at 20 outwardly thereof, in a substantially complementary manner to the bottom wall for increased pressurized strength. A centrally disposed neck 22, terminating in an outwardly rolled bead or curl 24, extends upwardly from the top wall portion 18. The neck opening permits the attachment of a closure cap, of the crown type for example, so that the container may be filled with draft beer or a carbonated beverage at a brewery or bottler, and thereafter capped for storage and subsequent distribution. The cap may then be removed by the consumer at some convenient time of use, and a dispenser assembly providing pressurizing means and valve-regulated spigot means attached by insertion into the exposed neck opening. In this way, a single dispenser assembly may be interchanged and repeatedly used with numerous containers, and the containers may be distributed and sold independently of the dispenser assembly, thereby eliminating the high cost and "fragile" handling requirements which arise in container arrangements having an integrally attached dispenser means.

A dispenser assembly indicated generally at 30, is provided and comprises a main body or head 32 which provides attachment means at its lower end for releasably securing the assembly in fixed relation within the neck of the container. A plurality of latch elements 34 are pivotally secured to the body 32 and cooperate with the outwardly rolled bead or curl 24 to secure the dispenser assembly to the container neck 22. The lower end of the body 32 provides a reduced diameter portion 36 adapted to be slidably received within the open neck of the container. For attachment of the dispenser assembly 30 to the container 10, it is merely necessary to push the reduced portion 36 downwardly into the open neck of the container until the latch elements 34 snap over the neck curl 24. Reference may be made to said R. S. Knapp et al. Patent No. 2,842,293 for a detailed description of the releasable attachment means.

The gas pressurizing means comprises a carbon dioxide bulb 40, as for example, a Sparklet bulb, manufactured by the Knapp Monarch Co., which is mounted by means of a bulb holder 42 within a threaded bore 44. The bulb 40 may be moved forwardly into the main body 32 by manu-

ally rotating the bulb holder 42. A retainer plug 46 cooperatively receives the neck of the bulb 40, and an O-ring 48 is provided for effecting a gas-tight seal. After sealing engagement of the bulb neck, continued forward movement of the bulb by manual screwing of the holder 42 will serve to effect a piercing of the forward end of the bulb by a piercing pin 50 supported within the plug 46. The piercing pin 50 provides a suitable gas flow passage therethrough, which communicates outwardly with the bulb interior and terminates inwardly at a valve seat 52 formed by the plug 46. In this way, the bulb 40 will first be sealed off and then pierced to effect delivery of the compressed gas therein to the valve seat 52.

A hollow and generally tubular regulator body 54 is defined by the main body 32, and the plug 46 provides an elongated collar 56 which extends into the interior of the body 54. A piston 58 is slidably reciprocable within the body 54, and an annular O-ring 60 provides a gas-tight pressure seal with the inner wall thereof. A cylindrical stem 62 of the piston 58 is slidably supported and guided within the plug collar 56. Gasket means defined by an O-ring 64 provides a seal between the cylindrical stem 62 and the circular inner wall of the collar 56. A valve seal disc 66 is carried at the free end of the stem 62 and is adapted to cooperate with the valve seat 52 to effect closure of the gas supply conduit of the piercing pin 50. A biasing spring 68 normally urges the piston 58 forwardly toward a valve-open position.

An end plate 70 provides a removable closure for the body 54, and cooperates with the free or forward end wall of the piston 58 to define a pressure regulator outlet chamber 54a wherein gas is maintained at an intermediate pressure between the very high pressure of the gas of bulb 40 and the liquid dispensing pressure maintained in container 10. A damping spring 72 is positioned in the space between the end plate 70 and the piston 58. The spring constant of the damping spring 72 is substantially greater than that of the biasing spring 68. The valve members 52 and 66 are in normally closed relation by reason of the gas pressure existing in intermediate chamber 54a and the greater effective working area of the piston 58 with respect to the valve member 66. An adjustable stop member 74 is threadedly received within the end plate 70 and provides a free end portion which is adapted to be engaged by the piston 58. A cross-bore 76 is formed in the piston stem 62, and communicates with a longitudinal bore 78 for gas by-pass flow extending through the piston 58 to its free face end in flow communication with the intermediate chamber 54a. The free end of the adjustable stop 74 is provided with suitable transverse slots 80 to avoid obstruction of flow through the passage 78 when the piston 58 is in seated engagement against the stop 74, as in the position shown in FIGURE 6 of the drawing. A sealing plug 82 insures tamperproof assembly of the parts with the adjustable stop 74 in a predetermined selected position.

When the valve members 52 and 66 are in open relation, gas will pass forwardly from the bulb 40 through the piercing pin 50 to the restricted annular sliding space between the elongated shank or stem 62 and the collar 56 intermediate the valve seat 52 and the sealing ring 64. The restricted annular sliding space between the stem 62 and collar 56 provides relatively large resistance to gas flow and this operates to materially reduce the gas pressure from the very high pressure source bulb 40. Gas at reduced pressure will then flow through the cross-bore or transverse bore 76 and through longitudinal bore 78 to the pressure regulator's outlet, intermediate-pressure chamber 54a. The spring 68 exerts a biasing force which will effect opening of the valve elements 52 and 66 when the intermediate pressure in the chamber 54a falls below that needed to maintain the constant pressure desired within the container 10 for dispensing operation. The damping spring 72 modulates movement of the piston away from the valve seat and serves to prevent "bouncing" of the piston stem 62 and its valve disc 66 when the

bulb 40 is initially pierced and before the pressures stabilize within the chamber 54a and before container 10 reaches the desired regulated or operating pressure. The adjustable stop 74 permits the various parts to be adjusted so as to obtain proper operation. The selection of the space or gap between the free end of the stop 74 and the free end of the piston 58 provides additional means for effecting gas pressure reduction from the very high pressure of bulb 40, by limiting the opening or movement of the valve disc 66 from valve seat 52.

A gas inlet duct 84 communicates at its one end with the chamber 54a and provides at its other end a threaded bore 86 in which a check valve screw 88 is received. A longitudinal bore 90 and intersecting cross bore 92 are formed in the screw 88. A resilient sleeve 94 normally tightly surrounds the outer end of the screw 88. When there is demand for pressurizing gas from container 10, pressure gas flows from the duct 84 and through the bores 90 and 92 will overcome the bias of sleeve 94 to effect escape between the outside wall surface of the screw 88 and the inner wall surface of the sleeve 94. The resilient strength of the sleeve 94 is selected so as to permit it to expand under a preselected pressure differential to thus provide an opening for the gas to pass into the container 10. When the normal equilibrium pressure differential is reached on both sides of the check valve screw 88, the sleeve 94 will again tightly engage about the screw 88 to prevent further gas flow.

It is particularly important that the check valve means 88 and 94 be disposed substantially entirely within the main body 32 and within the neck 22 of the container 10 so as to be entirely above the surface of the liquid to be dispensed. In addition, the enlarged head end of the screw 88, and the engagement of the free end of the resilient sleeve 94 against the annular shoulder defined by the screw 88 intermediate its head and its shank, serves to effect a lateral direction of the incoming gas flow. In this way, the liquid within the container 10, particularly in the case of beer or the like, will not be disturbed by a high velocity incoming gas flow, thus avoiding the risk of foaming.

A flexible siphon tube 100, preferably of suitable plastic material, reaches at its lower end to the container bottom, and is attached at its upper end to a shank 102 in a gas tight manner to prevent gas above the surface of liquid within the container from seeping therebetween and cause foaming of the liquid being dispensed. The tube 100 has a weighted lower end 104 which remains at all times closely adjacent the container bottom wall within the annular pocket formed between portions 14 and 16 thereof, so as to permit substantially complete emptying of liquid from the container. A sleeve 105 of suitable deformable plastic material, such as polyethylene or the like provides a fluid tight coupling between the siphon tube 100 and the shank 102. The shank 102 defines a vertically upwardly extending flow passage 103 having an outwardly downwardly inclined portion 109 which communicates at its outermost end with an enlarged flow chamber 110. A faucet body 112 provides a sharply downwardly inclined discharge spout 114 communicating at its inner end with the chamber 110. A fully rounded valve seat 116 is internally defined by the faucet body 112 at the outlet end of the chamber 110.

A self-closing push button type of control valve is provided for regulating flow of liquid from the container 10 through the spout 114. The control valve comprises a stem 118 and a valve head 120 of rubber or synthetic resinous material, which is slidably reciprocable within the faucet body 112 and is adapted to seal against the rounded valve seat 116. A push button 122 having packing means 124 and biasing spring 126 enables manual flow-opening movement of the valve seat 120 away from the valve seat 114 for discharge flow through the faucet body 112. The push button 122 is recessed within the faucet body 112 to avoid the risk of accidental valve

opening, and a pair of external finger grips 125 and 127 are provided to facilitate manual actuation.

It is a highly important feature of the present invention that a rod 128 of particular form and function is disposed at the lowermost or inlet end of the siphon tube 100 and within the flow passage defined thereby, as best seen in FIGURE 3 of the drawing. The rod 128 is suitably slotted at the inlet end of the siphon tube 100 to permit dispensing flow upwardly into the tube 100 through the annular conduit space defined between the outer surface of the rod 128 and the inner surface of the tube 100. The function of the rod 128 is to impart a spiral flow pattern to the liquid as it moves upwardly through the tube 100. In the specific structure illustrated in FIGURE 3, a spiral wire element 130 surrounds the rod 128, and the rod is formed with a slight upward taper. In this way, the liquid will be forced to move through a tortuous or spiral path. It will be understood that a variety of structural equivalents may be utilized to achieve this same function, and the use of such embodiments is contemplated as a one-piece rod having an external spiral groove or land cut therein and disposed in closely adjacent or contacting relation to the inner wall surfaces of the tube 100. It will also be understood that the spiral flow imparting means may also be disposed at a point upwardly within the tube 100, rather than at the inlet end as shown. It is important, however, that such means be readily removable to facilitate cleaning and replacement.

Safety valve means are provided in the event that damage to the pressure regulator structure should prevent its proper functioning and risk excessive pressurization of the container 10. As best seen in FIGURE 5, a passageway 132 communicates with the interior of the container 10 and with a vent chamber 134. A valve seat 136 is defined intermediate the passage 132 and chamber 134. A valve block 138 carries an O-ring 140 adapted to effect sealing engagement with the seat 136. A retaining screw 142, having a vent opening 143, provides support means for a biasing spring 144 which operates to shift the block 138 toward a position of seating engagement of the O-ring 140 on the valve seat 136. The particular biasing strength of the spring 144 will serve to maintain sealing closure of the safety valve until a predetermined dangerous pressure has been reached, at which point safety relief flow will be enabled by valve unseating.

In the practical operation of the structure disclosed herein, various major problems which characterize the handling of such readily foamy liquids as beer and the like are effectively eliminated or minimized. When the dispenser assembly 30 has been secured to a fresh container 10 of beer to be dispensed, the bulb 40 will be manually energized by movement into its piercing position within the pressure regulator device. At this point, a sudden high pressure surge of gas, at about 800 p.s.i., will move toward the container interior. Although pressure regulators have been known in the past for use in dispenser-container combinations, such devices have not provided a sufficient and economic means for avoiding pressure overrun when the gas supply bulb is pierced. The provision of a reciprocable piston member having an adjustable stop means and a damping spring effectively solves this problem in a simple and reliable manner. The initial sharp forward movement of the valve means effects a shifting of the piston 58 which is in turn damped by the spring 72 and controlled in extent by the adjustable stop 74 to achieve an optimum piston action for the desired operating pressures.

Prior known structures have been subject to a back flow of liquid from the container interior upwardly through the pressurizing passageways into the pressure regulator valve structure. In order to solve this problem, there is provided a novel check valve which permits

gas to flow into the container at the required pressurizing level, but which prevents any reverse flow. In particular, there is utilized the novel screw and sleeve structure 88-94 for accomplishing this objective.

Inordinate foaming is a very serious problem in any dispensing structures to be used with such liquids as beer. It has been discovered that it is a critical and essential requirement that the pressure at the discharge faucet be lower than the pressure within the container itself. The novel use of spiral flow imparting means within the siphon tube 100 serves to achieve this necessary pressure reduction between the container interior and the faucet spout.

A further requirement for a dispenser of the type disclosed, wherein a liquid which is subject to spoilage is to be stored and dispensed, is to prevent pockets of the liquid from being trapped and permitted to lie stagnant in the dispenser structure. This problem is particularly present within the discharge head or faucet spout. It is particularly important, therefore, that the entire faucet head 112 be disposed at a slightly downwardly inclined angle relative to the horizontal, and that all flow passages downstream of the dispensing valve means 116-120 be abruptly slanted so that no fluid will be retained outwardly of the valve seat where it would risk becoming sour. For this purpose the inclined passages 109 and 114 are provided.

The structure of the present invention provides a readily attached and detached dispenser device capable of providing efficient and uniform dispensing of beer and other ebullient liquids and of permitting their refrigerated storage over a substantial time for periodic dispensing. While there has been shown and described a particular embodiment of this invention, it will be obvious to those skilled in the art that various changes and modifications may be made therein without departing from the invention and, therefore, it is intended in the appended claims to cover all such changes and modifications as fall within the true spirit and scope of the invention.

What is claimed as new and is desired to be secured by Letters Patent of the United States is:

1. An improved pressure regulator for use with a container for ebullient liquid that utilizes a source of high pressure gas to effect pressurized selective flow of the ebullient liquid from the container; said pressure regulator comprising, in combination: a hollow regulator body, means defining a valve seat that is adapted to communicate with a source of high pressure gas, a piston member freely and slidably reciprocable within said hollow body in sealing relationship therewith to partially define a pressure outlet chamber spaced from said valve seat and adapted to be communicated with the interior of a container of ebullient liquid, an elongated annular collar surrounding said valve seat and extending toward said piston member, said piston member carrying a valve member having an elongated shank whose cross-section is similar to but only slightly less than the interior cross-section of the annular collar so as to be slidably disposed in said collar and to define a sliding space of restricted cross-section that offers relatively large resistance to gas flow therethrough, and the extended terminus of said shank being adapted for sealing engagement with the valve seat, gasket means carried on said elongated shank and slidably engaging said collar for effecting a seal therebetween for all positions of said piston member, by-pass conduit means for communicating gas under pressure from the sliding space region spaced axially between said gasket means and said valve seat to said pressure outlet chamber, thereby exposing the piston member to gas pressure that urges the valve member toward sealing engagement with the valve seat, and a coil spring surrounding the collar and engaging the piston member for automatically urging the piston member away from said valve

seat when the gas pressure in said pressure outlet chamber falls below a predetermined level.

2. An improved pressure regulator for use with a container for ebullient liquid that utilizes a source of high pressure gas to effect pressurized selective flow of the ebullient liquid from the container; said pressure regulator comprising, in combination: a hollow regulator body, means defining a valve seat that is adapted to communicate with a source of high pressure gas, a piston member freely reciprocable within said hollow body in sealing relationship therewith to partially define a pressure outlet chamber spaced from said valve seat and adapted to be communicated with the interior of a container of ebullient liquid, an elongated annular collar surrounding said valve seat and extending toward said piston, said piston carrying a valve member at one end thereof slidably disposed in said collar, said valve member and said collar defining therebetween a sliding space of restricted cross-section that offers relatively large resistance to gas flow therethrough, said valve member being adapted for sealing engagement with the valve seat, by-pass conduit means including a transverse passageway in said valve member communicating with the sliding space between the valve member and the collar, and an axial passageway through said piston communicating with said pressure outlet chamber, a spring engaging the piston to automatically move the piston away from the valve seat when the gas pressure in said pressure outlet chamber falls below a predetermined level, and damping means for modulating movement of the piston away from said valve seat.

3. An improved pressure regulator as in claim 2 including gasket means on said valve member slidably engaged with the interior of said annular collar and being disposed further from the end of the valve member than the transverse passageway communicating with said sliding space for effecting a seal between the valve member and the collar, whereby a preliminary pressure reduction of the gas is effected as the gas flows through said sliding space from the valve seat and into the transverse passageway.

4. A pressure regulator assembly comprising a main body having a flow chamber, a piston slidably mounted in said flow chamber in gas sealing relationship therewith, a damping spring mounted within said flow chamber to one side of said piston, an insert carried by said main body and defining a guide collar which projects into said flow chamber to the other side of said piston, said insert having a restricted flow passageway therethrough forming a valve seat at one end, a gas bulb piercing pin carried by said insert at the other end of the flow passageway and having a passageway therethrough and adapted for passing gas under pressure from a bulb through said flow passageway, a stem on said piston received in said guide collar and defining therewith a restricted flow space, a valve on the end of said stem cooperating with the seat for closing said flow passageway, a coil spring surrounding said collar and seated between said other side of said piston and said insert for normally biasing said valve towards its open position, a seal engaged between said collar and stem for preventing gas flow therebetween the portion of the stem between the seal and valve slidably cooperating with the guide collar, a pair of intersecting passageways in said stem and passing through the piston communicating said portion of the stem with said one side of the piston for conducting gas from said flow passageway through said restricted flow space, to the interior of the flow chamber on said one side of the piston, and an outlet from said flow chamber at said one side of the piston.

5. An improved pressure regulator for use with a container for ebullient liquid that utilizes a source of high pressure gas to effect pressurized selective flow of the

ebullient liquid from the container; said pressure regulator comprising, in combination: hollow regulator body means defining a gas inlet for communicating a source of high pressure gas thereto and an outlet for gas therefrom at a reduced pressure adapted to be supplied to the container of ebullient liquid, said regulator body means defining an inlet valve seat surrounding said inlet, an elongated collar member surrounding said inlet valve seat and arranged to communicate with said gas inlet, and a reduced-secondary-pressure chamber bounded in part by an elongated cylindrical wall of greater inner diameter than the inner diameter of said elongated collar; and two-stage pressure-reduction means for reducing the source of high pressure gas to a greatly reduced pressure that is operative for communication to the container of ebullient liquid, said pressure-reduction means including a first-stage means in said regulator body located between the source of high pressure gas and the chamber of reduced-secondary-pressure, which first-stage means includes a valve member having an elongated shank whose cross-section is similar to but only slightly less than the interior cross-section of the annular collar, so as to be slidably disposed in said collar and to define a sliding space of restricted cross-section that offers relatively large resistance to gas flow therethrough, means at one end of the elongated shank being constructed and arranged for sealing engagement with the inlet valve seat, gasket means carried on said elongated shank and slidably engaging the collar for effecting a seal therebetween, a piston movable with said elongated shank and slidably reciprocable within the elongated cylindrical wall portion of the reduced-secondary-pressure chamber with one side of the piston exposed to the pressure in said chamber, and by-pass conduit means for communicating the gas under pressure from the sliding space region located between the inlet valve seat and the said gasket means to said reduced-secondary-pressure chamber, the pressure in said reduced-secondary-pressure chamber acting against the piston to tend to move said piston and thereby said shank toward the valve seat for cutting off high pressure gas flow through said inlet, and the second-stage means of said pressure-reduction means including a flexible resilient member that is exposed to the pressure in the chamber of reduced-secondary-pressure and being arranged and constructed to control gas flow from said chamber through said outlet for the gas.

6. A device as in claim 5 including spring means for normally biasing the shank away from the inlet valve seat.

7. A device as in claim 5 including a stop means on said regulator body means for preventing too great movement by the piston and shank away from the valve seat upon initial application of a high pressure gas source to the inlet of the improved pressure regulator.

8. A device as in claim 5 including spring means for damping the movement of the piston and shank away from the inlet valve seat.

9. A device as in claim 5 wherein the flexible resilient member is constructed and arranged to serve as a check valve to prevent pressurized ebullient liquid from entering the reduced-secondary-pressure chamber of the pressure regulator.
